UNITED STATES PATENT OFFICE.

WADE BARNETT, OF NEW ORLEANS, LOUISIANA.

FLUSHING APPARATUS.

1,149,887.

Specification of Letters Patent. Patented Aug. 10, 1915.

Application filed December 2, 1914. Serial No. 875,153.

To all whom it may concern:

Be it known that I, WADE BARNETT, a citizen of the United States, residing at New Orleans, in the parish of Orleans and 5 State of Louisiana, have invented certain new and useful Improvements in Flushing Apparatus; and I do hereby declare the following to be a full, clear, and exact description of the invention, such as will enable 10 others skilled in the art to which it appertains to make and use the same.

The present invention relates to flushing apparatus and consists more particularly in an improved and substantial apparatus for 15 flushing closet bowls, which is designed to replace the open-cistern systems containing ball-float-actuated valves now commonly employed.

An object of the present invention resides 20 in providing an improved flushing apparatus wherein the delivery of the water from the cistern or reservoir will be under the control of either the pressure in the service system, or a device normally balanced by 25 the service and reservoir pressures, and arranged to have its balance destroyed when the reservoir empties.

It is another object of the present invention to provide a flushing apparatus of the 30 above character which will include an arrangement for insuring the filling of the bowl after the flushing operation has been effected.

My invention will be understood by reference to the accompanying drawings, in 35 which similar reference symbols indicate like parts in the several views.

Figure 1 is a vertical sectional view of a cistern or reservoir, illustrating one form of 40 an apparatus constituted in accordance with the present invention; Fig. 2 is an elevational view of the same taken at right angles to Fig. 1; Fig. 3 is an enlarged sectional view of the pressure-controlled latch device; 45 Fig. 4 is a similar view of a modified form of latch device; Fig. 5 is an elevational view of a system embodying a second form of apparatus of which the invention is susceptible; Fig. 6 illustrates in elevation a 50 substantially similar system disclosing the connection to a closet bowl; Fig. 7 is a vertical sectional view of a latching device as employed in conjunction with the apparatus shown in Figs. 5 and 6; Fig. 8 is a similar 55 view disclosing a slightly modified form of

device; Fig. 9 is a fragmentary elevational view of the delivery pipe illustrating a filling reservoir connected thereto; and Fig. 10 is a longitudinal sectional view of the same illustrating a modified form of filling reservoir.

Referring more particularly to Figs. 1-4 of the drawings, 1 designates an inclosed cistern or reservoir in open communication with a source of fluid supply through a connection 2, and connected to a closet bowl by means of a delivery pipe 3 of relatively large diameter.

The delivery pipe 3 is under the control of a self-closing valve 4 of any suitable 70 type, on the stem of which is mounted a quadrant or other device 5 to which is attached a chain 6 for actuating the quadrant to open the valve when it is desired to flush the bowl. The quadrant 5 normally occupies the position shown in dotted lines in Fig. 1, when the valve 4 is closed; and may be drawn down by the chain 6 to the full-line position to open the valve and permit the water in the cistern 1 to flow out through 75 the delivery pipe 3 and flush the closet bowl.

In order to insure the delivery of a predetermined quantity of water to the closet bowl for properly effecting the flushing operation, there is provided a device for preventing the automatic closing of the valve 4 immediately upon the release of the chain 6 and for holding said valve open a predetermined length of time, dependent upon the 80 pressure in the cistern 1. This device is shown more particularly in Fig. 3 to consist of a casing body 7, enlarged and dished at its upper end and coöperating with an enlarged and dished cap 8 to constitute a 85 chamber for a diaphragm 9, secured along its peripheral edge between said body and cap. The diaphragm 9 is connected to the upper end of a latch plunger 10 mounted to reciprocate through a stuffing box 11 formed in the casing body 7, and through 90 a guide bearing 12 supported from arms 13 joined at their opposite ends by a ring 14 threaded on the casing body.

As advantageously disclosed in Fig. 1, the 95 device is arranged to be connected to the bottom of the cistern 1 to one side of the delivery pipe 3, and is in communication with the cistern through a perforation 15 in the cap 8, whereby the pressure in the cistern is 100 105 110

utilized to act on the upper face of the diaphragm 9 and tend to force the latch plunger down. The lower free end of the latch plunger is beveled, as indicated at 16, to permit the quadrant 5 to ride thereover when moved to open the valve 4; and the end of the latch plunger is adapted to drop into a notch formed in the quadrant when the same is drawn down or to drop behind the same as shown in Fig. 1, and effectually prevent the return of the valve to closed position.

The action of the cistern pressure on the upper surface of the diaphragm 9 is arranged to be counteracted by a coil spring 17 encircling the latch plunger 10, and confined between the guide bearing 12 and a collar 18 fixed to the plunger; and the spring 17 is selected to be of a strength to overcome the cistern pressure when the latter falls below a predetermined degree and come into play to raise the latch plunger 10 and lift the end 16 thereof out of engagement with the quadrant 5 to release the valve 4 to its self-closing mechanism.

Referring in detail to Fig. 4, a slightly modified device is here shown to dispense with the diaphragm 9 and to substitute therefor a piston 19 connected to the latch plunger and reciprocating in a cylinder 20. In all other substantial details the device is the same as that shown in Fig. 3 and the operation similar.

The operation of the apparatus is as follows: Water flows in through the connection 2 and fills the cistern 1, compressing the entrapped air therein above the water until the pressure of the latter becomes equal to and balances the supply pressure. The apparatus is now in readiness for action and when desired the chain or other connection 6 may be pulled to revolve the quadrant 5 from the position shown in dotted lines in Fig. 1 to the full-line position therein shown, which action operates to open the valve 4 and permit the water to discharge through the delivery pipe 3 whereby the water is conducted to the bowl. When the quadrant is so actuated the latch plunger 10, under the influence of the diaphragm 9, drops down, as above described, and prevents the valve 4 from closing by its automatic action and the chain may be immediately released. The latch plunger 10 is maintained in engagement with the quadrant 5 by the cistern pressure exerted on the diaphragm 9 or piston 19, as the case may be, and consequently when the same falls below a predetermined degree the spring 17 is arranged to come into play and raise the plunger out of the path of the quadrant. The valve 4 will thereby be permitted to close and may have any suitable dampening means associated therewith, if found necessary or desirable, to cause the valve to close slowly and insure the delivery of an amount

of water sufficient to fill the bowl after flushing. It will be understood that the delivery pipe 3 is of relatively large diameter, as compared to the connection 2, so that the incoming water from the supply source will not build up the pressure in the cistern 1 as rapidly as it is reduced; otherwise the apparatus would not operate as described. After the valve 4 has completely closed it will be found that the pressure will quickly build up in the cistern in readiness for the next actuation.

In the constructions illustrated in Figs. 3 and 4, the diaphragm casing body 7 and the cylinder, respectively, are provided with openings 21, which, as shown in Figs. 1 and 2, are connected by a pipe 22 for conveying off any water that may leak around the diaphragm and piston and conducting same to the delivery pipe 3.

Referring more particularly to Figs. 5 to 8, inclusive, a modified structure is here shown, operated by the direct action of the supply pressure, which latter is normally balanced by the cistern or reservoir pressure and permitted to act only when the latter falls below a predetermined degree.

In this system, as in that first described, is comprised a cistern or storage pipe or reservoir 23, which may be located within the wall of the room where installed, and which is connected with the closet bowl 24 by a delivery pipe 25. The connection 26 from the supply source is not, in this instance, coupled directly with the storage reservoir 23, but through a pipe 27 of relatively small diameter and consequent great frictional resistance. The self-closing valve 28, quadrant 29 and chain 30 are similar in construction and operation to the corresponding parts shown and described in connection with the first form of the apparatus.

The valve releasing device is, however, of slightly different construction, one form of which is shown in Fig. 7 and comprises a casing body 31 formed with an enlarged and dished upper end and with an enlarged and dished lower end of relatively greater diameter for coöperating with dished caps 32 and 33, respectively, to provide a pair of chambers of unequal size. In the chambers are secured diaphragms 34 and 35, connected each to the common latch plunger 36, the latter being mounted to reciprocate in the body 31 and constantly acted on by a spring 37 to move the plunger upwardly.

The casing body 31 is constructed with nipples 38 and 39 for connection by pipes 40 and 41 in communication, respectively, with the supply source 26 and the delivery pipe 25, as shown in Figs. 5 and 6.

The caps 32 and 33 are respectively provided with perforations 42 and 43 to receive a pipe 44 leading to the drain for carrying off leakage. As seen in Fig. 6, a pipe

45 may be arranged between the supply 26 and the delivery 25 for filling the reservoir 23 after the valve 28 has been closed. Such pipe 45 may replace the pipe 27, or the same 5 may be used as auxiliary thereto, and must be of similar great frictional resistance in order to prevent a sudden reduction of pressure on the diaphragm 34 when the reservoir 23 begins to empty.

10 Referring now to Fig. 8, wherein is disclosed a modified form of valve releasing device, the casing body 46 is constructed with upper and lower cylinders 47 and 48 of unequal diameters for receiving pistons 49 and 50, corresponding to the diaphragms 34 and 35 and connected to the common latch plunger 36. The device is in other respects similar in construction and operation to the device in Fig. 7 and is provided 15 with connections similarly numbered. The operation of this form of the invention is as follows: The chain 30 is pulled and the quadrant moved to open the valve 28 as will now be understood. The reservoir 23 and supply connection 26 being in a balanced state, the pressure on the diaphragms 34 and 35, or on the pistons 49 and 50, as the case may be, will be equal; and as the diaphragm 35 is of relatively greater 20 surface area the pressure thereon will preponderate and force the latch plunger 36 down to engage the quadrant 29 and lock the same against return movement. After the reservoir 23 has emptied or practically 25 emptied the pressure will fall in the pipe 41 and the supply pressure remaining constant will thereupon raise the diaphragm 34 and lift the latch plunger 36 out of engagement with the quadrant 29. The valve 28 will then close as above described, and the pressure will build up in the reservoir through either the pipes 27 or 45.

Having special reference to Fig. 9, in the delivery pipe 25 is included a Venturi section 51 connected by a pipe 52 with the upper end of a storage receptacle 53. The receptacle 53 is joined at its lower end to the delivery pipe 25 by a curved section 54. This arrangement provides for filling the receptacle 53, while the reservoir 23 is discharging, as will be understood; and after the flushing operation the receptacle 53 will empty slowly and fill the bowl.

Still another arrangement for effecting 55 this same object is shown in Fig. 10, and comprises an annular receptacle 60 surrounding the delivery pipe 25 and communicating therewith through upper and lower perforations 61 and 62. At the base of the 60 receptacle 60 the pipe 25 is formed with a constricted neck or nozzle 63, which checks the velocity of the water and causes same to flow in through the perforations 62, while air is expelled through the perforations 61.

65 After the discharge has ceased in pipe 25,

the receptacle 60 will empty slowly through perforations 62 and fill the closet bowl.

It is to be understood that the spring 37 70 may be dispensed with in Figs. 7 and 8; and that a valve releasing device may be constructed of a combined diaphragm and piston in place of the constructions there shown. It is also within the contemplation of the invention to construct the valve and releasing device in one piece, and to make 75 such other changes as may be needed.

I claim:

1. In an apparatus of the character described, the combination of an inclosed reservoir in open communication with a source of fluid supply, a delivery pipe connected to said reservoir, a self-closing valve controlling the outlet through said delivery pipe, a connection for operating said valve, a casing in constant communication with 80 said reservoir, a latch slidably mounted in said casing and disposed angularly with respect to the path of said connection, said latch being arranged to engage said connection and prevent closing of said valve, 85 means mounted in said casing and actuated by the fluid pressure to normally project said latch into engagement with said connection, and means for moving said latch to disengage said connection and retreat out of 90 the path of the same whereby to permit the valve to immediately close when the pressure falls below a predetermined degree, substantially as described.

2. In an apparatus of the character described, the combination of an inclosed reservoir in open communication with a source of fluid supply, a delivery pipe connected to 100 said reservoir, a self-closing valve located in and controlling the outlet through said delivery pipe, an oscillating connection for operating said valve, a casing in constant communication with said reservoir, a latch mounted to reciprocate in said casing and arranged to engage said connection and prevent closing of said valve, said latch being disposed angularly with respect to the path of said connection, means mounted in said casing and actuated by the fluid pressure to 105 normally project said latch into engagement with said connection, and means independent of said self-closing valve for moving said latch to disengage said connection and retreat out of the path of the same whereby to permit the valve to immediately close 110 when the pressure falls below a predetermined degree, substantially as described.

3. In an apparatus of the character described, the combination of an inclosed reservoir in open communication with a source of fluid supply, a delivery pipe leading from said reservoir, a self-closing valve controlling the outlet through said delivery pipe, a connection for operating said valve, 125 a normally-projected latch for engaging 130

4
said connection and preventing the closing of said valve, and means connected to said latch and actuated by said reservoir and supply pressures to project said latch when the pressures are balanced and to retract said latch when the reservoir pressure falls to disengage said connection and permit the valve to close, substantially as described.

5. In an apparatus of the character described, the combination of an inclosed reservoir in open communication with a source of fluid supply, a delivery pipe leading from said reservoir, a self-closing valve controlling the outlet through said delivery pipe, a connection for operating said valve, a casing in communication with said reservoir and supply source, a latch mounted to reciprocate in said casing and arranged to engage said connection to prevent the closing of said valve, and means located in said casing and actuated by said reservoir and supply pressures to project said latch when the pressures are balanced and to retract said latch when the reservoir pressure falls to disengage said connection and permit the valve to close, substantially as described.

6. In an apparatus of the character described, the combination of an inclosed reservoir in open communication with a source of fluid supply, a delivery pipe leading from said reservoir, a self-closing valve controlling the outlet through said delivery pipe, a connection for operating said valve, a casing constructed to provide a pair of compartments in communication one with the reservoir and one with the supply source, a latch mounted to reciprocate in said casing and extending into each of said compartments, said latch being arranged to engage said connection and prevent the closing of said valve, and means located in each of said compartments and connected to said latch, said means being actuated by said reservoir and supply pressures to project said latch when the pressures are balanced and to retract said latch when the reservoir pressure falls to disengage said connection and permit the valve to close, substantially as described.

7. In an apparatus of the character described, the combination of an inclosed reservoir in open communication with a source of fluid supply, a delivery pipe leading from said reservoir, a self-closing valve controlling the outlet through said delivery pipe, a connection for operating said valve, a casing in communication with said reservoir and supply source, a latch mounted to reciprocate in said casing and arranged to engage said connection to prevent the closing of said valve, and means located in said casing and actuated by said reservoir and supply pressures to project said latch when the pressures are balanced and to retract said latch when the reservoir pressure falls to disengage said connection and permit the valve to close, substantially as described.

8. In an apparatus of the character described, the combination of an inclosed reservoir in open communication with a source of fluid supply, a delivery pipe leading from said reservoir, a self-closing valve controlling the outlet through said delivery pipe, a connection for operating said valve, a casing constructed to provide a pair of compartments in communication one with the reservoir and one with the supply source, a latch mounted to reciprocate in said casing and extending into each of said compartments, said latch being arranged to engage said connection and prevent the closing of said valve, and means located in each of said compartments and connected to said latch, said means being actuated by said reservoir and supply pressures to project said latch when the pressures are balanced and to retract said latch when the reservoir pressure falls to disengage said connection and permit the valve to close, substantially as described.

In testimony whereof, I affix my signature, in presence of two witnesses.

WADE BARNETT.
